UNITED STATES PATENT OFFICE

91,555

DESIGN FOR A SALT AND PEPPER SHAKER ASSEMBLY

Helen Hughes Dulany, Chicago, Ill.

Application January 15, 1934. Serial No. 50,402

Term of patent 3½ years

To all whom it may concern:

Be it known that I, HELEN HUGHES DULANY, a citizen of the United States, residing at Chicago, in the county of Cook and State of Illinois, have invented a new, original, and ornamental Design for a Salt and Pepper Shaker Assembly, of which the following is a specification, reference being had to the accompanying drawing, forming part thereof.

Figure 1 is a perspective view, showing the salt

and pepper containers in assembled position on the unit base.

Figure 2 is a perspective view of the assembly, with one of the shakers removed from socket, thus showing more clearly the details of assembly generalized in Figure 1.

I claim:

The ornamental design for a salt and pepper shaker assembly as shown and described.

HELEN HUGHES DULANY.
